UNITED STATES PATENT OFFICE

KORNEL ISSAR, OF DETROIT, MICHIGAN

HUMIDIFIER FOR GAS ENGINES

Application filed April 3, 1930. Serial No. 441,203.

The object of my invention is to produce a humidifier adapted for introducing moisture into the fuel gases before entering the same into the engine cylinder combustion chambers.

Another object is to produce a humidifier for introducing moisture into the engine fuel gases that is always under direct control of the operator of the engine.

10 A further object is to produce a gas engine humidifier that can be synchronized with and operated by the carburetor operating mechanism, in a manner for varying the amounts of moisture introduced in the fuel 15 gas directly with the speed of the motor.

A still further object is to produce a special humidifier tank that will disintegrate the water placed therein so that it may be drawn therefrom in a vapor form of uniform 20 density.

A further object is to produce a humidifier for gas engines that is simple in construction, easily and efficiently operated and can be manufactured at a low cost.

25 These several objects are attained in the preferred form by the construction and arrangements of parts more fully hereinafter set forth.

Similar parts on all drawings are marked 30 by similar numerals or letters.

Fig. 1 is a front view of the humidity tank showing the inlet and outlet passage connections.

Fig. 2 is a top view of the tank as shown in 35 the Fig. 1, showing the relative positions of the various tank openings.

Fig. 3 is a vertical sectional view taken on the line 3-3 of the Fig. 2 showing the relative position of the operating parts as 40 mounted within the tank.

Fig. 4 is a horizontal sectional view through the tank body taken on the line 4-4 of the Fig. 1 showing the construction of the water float and means for attaching the 45 indicator rod thereto.

Fig. 5 is an assembled view showing my device as installed in an automobile and connected to the engine with the means for operating and regulating same.

50 I will now describe more fully the detailed

construction of my device, referring to the drawings and the marks thereon.

In general my device comprises a sealed liquid tank having means for injecting water therein. The tank is provided with a water 55 indicator float, and inlet and outlet ports covered by suitable valve and shields for preventing water from flowing from either port in a liquid form. The tank outlet port being connected with the engine fuel intake manifold by a pipe line within which is installed suitable operating and regulating valves.

The tank —1— is preferably made of sheet metal, cylindrical in form, closed at the bottom and provided with a cap top —2— tightly fitted and sealed thereon, forming a closed air tight tank. The bottom of the tank —1— is formed with a threaded opening —3— therethrough and carries mounted therein a curved funnel tube —4— also threaded at 60 the stem end —5— for engaging the threaded tank opening —3—, projecting the tube end —5— vertically within the tank chamber —6— and positioned therein along the centerline of the tank. The funnel tube —4— is securely attached to the tank bottom by the lock nut —7— tightly screwed thereon, and the joint made water tight by the gasket —8— placed therebetween. The funnel tube 65 —4— is curved at right angles to the threaded stem —5—, and formed with an air bell —9— on the outer end thereof, positioned to face the front side of the tank when installed on an automobile. The top end of the stem —5— is formed with an open spherical valve seat —10— thereon. Mounted on the valve seat —10— is a true hemispherical valve cap —11—, preferably made of light sheet metal, designed and fitted thereto to maintain a water tight joint with the seat for all positions 70 of the valve cap. On the bottom side of the valve cap —11— is attached a light coil spring —12— which is extended to the curved portion of the funnel tube —4— and attached thereto by the adjusting screw —13— mounted in the funnel tube wall. The adjusting screw 75 —13— is provided with a lock nut —14— for fixedly retaining same in any adjusted position, the screw —13— providing means for varying the tension of the connected spring 80

Fig. 1 is a front view of the humidity tank showing the inlet and outlet passage connections.

Fig. 2 is a top view of the tank as shown in the Fig. 1, showing the relative positions of the various tank openings.

Fig. 3 is a vertical sectional view taken on the line 3-3 of the Fig. 2 showing the relative position of the operating parts as mounted within the tank.

Fig. 4 is a horizontal sectional view through the tank body taken on the line 4-4 of the Fig. 1 showing the construction of the water float and means for attaching the indicator rod thereto.

Fig. 5 is an assembled view showing my device as installed in an automobile and connected to the engine with the means for operating and regulating same.

I will now describe more fully the detailed

—12— on the attached valve cap —11—, and for maintaining a water tight joint with the valve seat —10—, yet sufficiently free to allow an intake of air therethrough when subjected to engine cylinder vacuum. Within the tank top —2—, preferably on the back side of the tank is mounted a threaded filling plug —15—, tightly fitted therein and providing means for injecting water within the tank chamber —6—. At the opposite side of the top —2— is formed an outlet port —16— extending through the cap wall and opening into the tank chamber. Mounted within the outlet port —16— is a feed pipe —17— securely attached to the top —2— by the lock nut —18— engaging a threaded boss —19— formed on the tank top concentric with port —16—. Directly beneath the outlet port —16— and within the tank chamber —6— is mounted a fine screen cone filter —20— securely attached to the inside wall of cap —2— and positioned concentric with the port —16—. Outside of the cone filter —20— is placed a coarse screen cone filter —21— of larger dimensions, positioned concentric with the cone filter —20— and also securely attached to the inside wall of the cap —2—. The two cone screen filters are separated from each other and provide a small air space therebetween. It is found a very efficient combination is attained by using a fine screen of about $\frac{1}{4}$ inch mesh, and a coarse screen of about $\frac{1}{2}$ inch mesh or slightly larger. The purpose of the double screen is to disintegrate the water from a liquid form into a vapor form by breaking the water up into fine particles as air is drawn therethrough. Within the tank chamber —6— is mounted a water float —22—, made either of cork or of hollow metal, and formed with a centrally located hole —23— passing therethrough, said float being slightly smaller than the tank chamber and free to rise and fall therein. Mounted on the top side of the float —22— is a straight indicator rod —24— positioned at right angles to the float top surface, and is fixedly attached to the float by the extended spider arms —25— encircling the central float opening —23—. The rod —24— is extended through the bearing —26— formed in the tank top —2— at the center thereof, and indicates the amount of water within the tank, said bearing being as nearly air tight as possible to allow free movement of the rod therethrough.

The tank —1— is to be mounted on the dash —27— of an automobile body, and positioned adjacent to the auto engine —28—, preferably at a height slightly above the engine top and in line with the engine fuel intake manifold —29—. The tank —1— may be securely attached to the auto dash —27— by the clip bands —30—, or by any other suitable means desired, but in all cases the tank —1— must be positioned thereon with

the air intake bell —9— facing the front of the engine and in the direction of the auto travel. The feed pipe —17— as mounted on the top of the tank —1— is extended over the engine intake manifold —29— and is connected thereto at a point directly over the center of the attached engine carburetor —31—, the pipe passage opening into the manifold chamber. Mounted on the feed pipe —17—, adjacent the engine fuel intake manifold —29— is a regulating feed valve —32—, preferably of the butter-fly type standard valve although other types of suitable valves may also be used, the valve —32— being operated by the valve lever —33— attached thereto. The lever —33— is pivotally connected to the carburetor operating lever —34— by the connecting rod —35—, synchronizing the movement of the feed valve with the movement of the carburetor valve —36—. Also mounted on the feed pipe —17— and directly above the feed valve —32— is a needle adjusting valve —37—, of any standard type, and carries attached to the valve stem —38— an operating rod —39— which is extended to the instrument board —40— of the auto body —41—, and in a position for convenient adjustment of the valve by the auto operator. The carburetor valve lever —34— is connected to the auto accelerator pedal —42— by the rod —43— in the ordinary manner.

When my humidifier is properly installed on an automobile and the tank —1— partially filled with water, the oscillating engine pistons will create a vacuum within the engine intake manifold —29—, transmitting same directly to the connected tank chamber —6— through the pipe —17—, drawing air into the tank chamber through the funnel tube —4— and up through the water contained within the tank. A portion of the water being allowed to pass through the float hole —23— and splash against the coarse screen cone filter —21—, retaining particles of water within the screen meshes by capillary attraction, and always maintaining a uniform film of water throughout the coarse cone surface. The water particles within the coarse screen cone filter are drawn into the meshes of the fine screen cone filter —20— by the vacuum of the engine oscillating pistons, and is there broken into a fine mist, resulting in practically a vapor and thoroughly saturating the air drawn therethrough before the same is taken into the engine manifold —29—. The passage opening through the feed pipe —17— is regulated by the needle valve —37— for a constant flow therethrough, and when once properly adjusted remains the same, while the supply of humidified air is regulated by the feed valve —32—, actuated by the carburetor mechanism. The feed valve —32— may be set to open and close directly with the car-

buretor valve if desired, or it may be adjusted so as to increase or decrease the moisture flow therethrough as the connected carburetor valve is operated, varying the amounts of humidified air to the most efficient proportions for the various engine velocities.

Having fully described my humidifier for gas engines, what I claim as my invention and desire to secure by Letters Patent is:

1. A humidifier adapted for introducing moisture within the fuel intake manifold of a gas engine and used in combination therewith, comprising a closed liquid tank having means for entering air through the tank bottom, said tank having an outlet port formed through the top thereof, double screen cone filters of different screen mesh mounted over said outlet port within the tank chamber, a float water indicator mounted within said tank chamber, a feed pipe mounted on said tank connecting same with the engine fuel intake manifold through the screened port and filters, valve means mounted within said feed pipe for regulating the flow of moisture therethrough.

2. A humidifier adapted for introducing moisture in a gas engine fuel intake manifold and used in combination therewith, comprising a closed liquid tank having an air valve mounted within the tank bottom, said tank being formed with an outlet port through the top thereof and opening into the tank chamber, a fine cone screen filter mounted over said outlet port within the tank chamber, a coarse cone screen filter mounted over said outlet port and over said fine cone screen filter within the tank chamber, a water float mounted within said tank chamber, a feed pipe connected to said outlet port and leading to an engine fuel intake manifold, regulating valves mounted within said feed pipe, one of which is connected with the engine carburetor operating mechanism for regulating the flow of humidified air in proportions with the engine fuel.

3. A humidifier adapted for introducing moisture in a gas engine fuel intake manifold and used in combination therewith, comprising a sealed liquid tank having an air passage with air valve installed mounted in the tank bottom, said tank being formed with an outlet port through the tank top opening into the tank chamber, a fine screen cone filter mounted over said outlet port within the tank chamber, a coarse screen cone filter of larger dimensions mounted over said outlet port and over said fine screen cone filter within the tank chamber, said screens being separated from each other, a water float and indicator mounted within the tank chamber and free to move vertically therein, a feed pipe mounted on said tank connecting the double screened outlet port with the fuel intake manifold of a gas engine, a needle

valve mounted within said feed pipe for regulating the passage opening therein, an operating valve mounted within said feed pipe actuated by direct connection with the engine carburetor operating mechanism for regulating the supply of humidified air admitted in the engine manifold.

In witness whereof I sign these specifications.
